Inventors

UNITED STATES PATENT OFFICE.

THOMAS C. CLARKE AND ADOLPHUS BONZANO, OF PHILADELPHIA, PA.

IMPROVEMENT IN CONNECTIONS FOR IRON AND STEEL BRIDGES.

Specification forming part of Letters Patent No. 117,048, dated July 18, 1871.

To all whom it may concern:

Be it known that we, THOMAS C. CLARKE and ADOLPHUS BONZANO, of the city of Philadelphia and State of Pennsylvania, have invented certain new and useful Improvements in Connections for Iron and Steel Bridges; and we do hereby declare the following to be a full, clear, and exact description of the same, reference being had to the accompanying drawing making a part of this specification, in which—

Figures 1, 2, and 3 represent, respectively, side, sectional, and end views of an improved mode of connecting wrought-iron columns by means of a cast-iron or steel joint-box having pockets for lateral struts and holes for eyebolts that unite the struts and columns.

To enable those skilled in the art to make and use our invention, we will proceed to describe the same with reference to the drawing, first premising that our invention consists in the combination of a cast joint-box and lateral struts with pins passing through them and adjustable eyebolts receiving said pins, and drawn together in the interior of or through the body of the box. The cast-iron or steel joint-box is shown at Y, having pockets or flanges at a for receiving the lateral struts V, which are of the "Phoenix" or hollow and flanged kind. Through these lateral struts or braces V are passed pins c, which pins

also pass through the eyes of eyebolts e, which eyebolts, if the struts are diametrically opposite each other on the joint-box, pass into the center of the joint-box, and are there caught, held, and tightly drawn up by a turn or screw-buckle, f. If a third or a single strut is to be connected with the joint-box similar provision is made to receive it, but its eyebolt e should extend clear through the joint-box, and be caught and held there by a nut outside of said box. The top and bottom of the joint-box are made to receive and hold columns, if so desired, or one only if but one is to be used. If four struts are used then they can be held in pairs by the turn-buckle f, as described. The tie-rods W, when used, may be united to the pins c by means of straps g.

Having thus fully described our invention, what we claim herein as new, and desire to secure by Letters Patent, is—

In combination with a joint-box and with lateral struts thereon, the pins passing through the struts and through the eyes of the adjustable bolts which pass into or through said joint-box, substantially as described.

THOMAS C. CLARKE.
A. BONZANO.
